UNITED STATES PATENT OFFICE.

NATHAN M. LOWER, OF SCHENECTADY, NEW YORK, ASSIGNOR TO LOCOMOTIVE STOKER COMPANY, OF WILMERDING, PENNSYLVANIA, A CORPORATION OF PENNSYLVANIA.

FUEL-DISTRIBUTER.

1,207,422.

Specification of Letters Patent.

Patented Dec. 5, 1916.

Application filed July 1, 1915. Serial No. 37,443.

To all whom it may concern:

Be it known that I, NATHAN M. LOWER, a citizen of the United States, residing at Schenectady, in the county of Schenectady 5 and State of New York, have invented a certain new and useful Improvement in Fuel-Distributors, of which improvement the following is a specification.

This invention relates to fuel distributors 10 for furnaces, and more particularly to mechanical stokers for boiler furnaces, in which fuel is fed through a discharge pipe extending through an opening in the furnace wall and distributed over the grate by 15 means of a blast or jet of steam or other fluid under pressure, as set forth in the prior Patent No. 1,130,443, of March 2, 1915.

One of the objects of my present invention is to provide an improved detachable 20 distributor hood which may be attached to the end of the fuel pipe within the furnace for more effectually distributing the fuel at one or both sides of the furnace; and another object is to provide improved means 25 for protecting the hood from the excessive heat of the furnace and thereby greatly increasing the useful life of the same.

In the accompanying drawings: Figure 1 is a side elevation of one form of my improved distributor hood attached to the end 30 of the shank of the fuel pipe extending through an opening in the water leg of a boiler furnace, the water leg of the boiler being indicated in section; Fig. 2, a front elevation of the distributor hood; Fig. 3, a longitudinal section of the same taken on the line 3—3 of Fig. 2; Fig. 4, an inverted plan of the same; Fig. 5, a longitudinal section taken on the line 5—5 of Fig. 2; Fig. 6, 35 a transverse section taken on the line 6—6 of Fig. 3; Fig. 7, an inverted plan showing a modification; Fig. 8, a longitudinal section taken on the line 8—8 of Fig. 7; Figs. 9 and 10, a side and front elevation, respectively, 40 of the same; Fig. 11, an inverted plan showing another modification; Fig. 12, a side view of the same; and Fig. 13, a transverse section taken on the line 13—13 of Figs. 11 and 12.

According to the construction shown in Figs. 1 to 6 of the drawings, my improved distributor hood, 23, comprises a metal casting formed with a substantially flat top wall, 7, having a downwardly extending

side wall or flange, 8, flaring toward its forward end, and extending the full length of the hood at one side, and a shorter wall, 9, at the other side extending forward only about one half the distance. The shorter wall, 9, is preferably located on the side 60 of the hood toward the side of the furnace, and for deflecting a portion of the fuel laterally toward the side of the grate, a curved flange, 10, is provided depending from the top wall, 7, and extending from the middle portion of the hood around to the side thereof near its front end, and in a direction substantially at right angles to the longitudinal center line of the distributor. By this means a portion of the fuel discharged 70 through the distributor is deflected by this curved flange and distributed over the side of the grate, while the main portion of the fuel is discharged in a forward direction, and by engaging the under surface of 75 the top wall, 7 and the side wall, 8, is spread out and distributed uniformly over a longitudinal section of the grate area. The forward end of the side wall, 9, may be formed with a laterally extending flange, 11, to assist in the distribution of the portion of fuel deflected by the curved flange, 10.

In order to protect the metal casting from the excessive heat of the furnace, I provide a layer or covering of refractory material, 85 12, such as fire clay or other composition, which may be applied in a plastic state, extending over the top of the wall, 7, and down over the side wall, 8, the same being rigidly secured upon the metal casting by 90 means of integral ribs, 13, formed upon the outer surface of the casting, and embedded within said material. Any desired number and arrangement of ribs may be employed.

The distributor hood is designed to be attached, by suitable flanges, 4, to the end of the shank, 17, of the elbow, 16, extending from the fuel pipe, 15, through the opening in the water leg, 18, of the furnace wall, as shown in Fig. 1, the elbow being provided 100 with an air blast, 20, and a stem jet, 19, for forcing the fuel through the distributor.

The modification shown in Figs. 7 to 10 of the drawings, is similar to that above described, except that two curved deflecting flanges, 10^a and 10^b, are employed meeting together at substantially the center line of the hood and curved outward toward the

opposite sides thereof. These flanges extend downward from the flat top wall, 7, and the side walls, 8 and 9, terminate short of the outer ends of the curved flanges to allow a 5 certain part of the fuel to be discharged laterally over the grate at the sides of the hood. Where the distributor is located at one side of the center of the furnace, the curved deflecting flange on the side toward 10 the center may be of less vertical height than the other curved flange, in order that more fuel may be thrown forward beneath the lower edge of the flange and longitudinally of the grate, on the side toward the center than on the other side.

In the construction shown in Figs. 11, 12 and 13, the curved flange, 10, at one side is substantially the same as shown in Fig. 4, while a smaller and shorter curved flange, 20 10°, is provided on the other side of the hood, leaving a free open space between the inner ends of the two curved flanges, through which a portion of the fuel may be discharged longitudinally to the forward 25 part of the grate. An opening, 11a, is formed in the side wall, 8, at the outer end of the small curved flange, 10°, for discharging a portion of the fuel laterally over the grate.

30 In all of the modifications a portion of the fuel will be thrown directly forward beneath the lower edge of the curved deflecting flanges, and on to the forward part of the grate, while another portion will be deflected laterally by one or both curved flanges, and be discharged laterally at one or both sides of the distributor.

The protective fire clay covering, 12, may be applied to all of the modified forms of distributor hoods, and, as shown in Figs. 40 7 and 8, the top wall, 7, is provided with flaring openings to assist in securing the protective covering.

Having now described my invention, what 45 I claim as new and desire to secure by Letters Patent is:

1. In a mechanical stoker for boiler furnaces, the combination with a fuel discharge pipe extending through an opening in the furnace wall, of a distributor hood connected to the end of said pipe within the furnace, said hood comprising a casting having a substantially flat top wall, side walls, and a depending curved flange extending from the middle portion of said hood around to the side and beyond the end of the side wall for discharging a portion of the fuel laterally toward the side of the furnace.

50 2. In a mechanical stoker for boiler fur-

naces, the combination with a fuel discharge 60 pipe extending through an opening in the furnace wall, of a distributor hood detachably connected to the end of said pipe within the furnace, said hood comprising a casting having a substantially flat top wall, side 65 walls, and a curved vertical flange projecting downward from the under surface of said top wall and extending around to the side of the casting and beyond the end of the side wall for deflecting a portion of the fuel laterally toward the side of the furnace.

3. A fuel distributor for furnaces comprising a hood adapted to be detachably connected with a fuel pipe within the furnace, and formed with side walls and a flat 75 top wall having a depending curved flange extending from the middle portion thereof around to one side and beyond the end of the side wall for deflecting a portion of the fuel laterally toward the side of the furnace. 80

4. A fuel distributor for furnaces comprising a hood adapted to be detachably connected with a fuel pipe within the furnace, and formed with two vertical side walls and a flat top wall having two depending curved flanges extending from the middle portion of said hood around to the opposite sides thereof and beyond the side walls for deflecting a portion of the fuel laterally over the grate at both sides of the 90 hood.

5. A fuel distributor for furnaces comprising a hood adapted to be detachably connected with a fuel pipe within the furnace, and formed with a flat top wall having two depending curved flanges extending from the middle portion of said hood around to the opposite sides thereof for deflecting a portion of the fuel laterally over the grate at both sides of the hood, one of said deflecting flanges being of less vertical height than the other. 95

6. A fuel distributor for furnaces comprising a hood adapted to be detachably connected with a fuel pipe within the furnace, and formed with two side walls and a flat top wall having two depending curved flanges extending from the middle portion of said hood around to the opposite sides thereof and beyond the side walls for deflecting a portion of the fuel laterally over the grate at both sides of the hood, there being a free and unobstructed passage between the inner ends of said flanges at the middle portion of said hood for the discharge of fuel forward longitudinally of the grate. 100 110 115
